UNITED STATES PATENT OFFICE

ESMOND PHILIP GOODWIN WRIGHT AND GEORGE CLIFFORD HARTLEY, OF ALDWYCH, LONDON, ENGLAND, ASSIGNEES TO INTERNATIONAL STANDARD ELECTRIC CORPORATION, OF NEW YORK, N. Y.

AUTOMATIC OR SEMIAUTOMATIC TELEPHONE EXCHANGE SYSTEM

Application filed January 6, 1931, Serial No. 506,884, and in Great Britain January 7, 1930.

This invention relates to automatic or semi-automatic telephone exchange systems.

The main problem to which the present invention relates concerns the provision of automatic telephone facilities in large densely populated areas. Such areas comprise a number of exchanges connected by a junction network in such a way that calls can be set up between any two of the exchanges either directly or via one or more intermediate exchanges. The subscribers in each exchange are identified by numbers, usually of four figures, and as these numbers are repeated in the different exchanges, code letters, usually three in number, are prefixed to the subscribers' number and are characteristic of the exchanges to which they belong.

In order to reach the particular subscriber from any part of the network, his number, including the code letters, is dialled, in response to which a path to the wanted exchange must be set up, and the particular subscriber thereat selected. The selection within the wanted exchange will be carried out in response to the numerical digits in the same way wherever the call comes from, but it is obvious that the path to be selected between the originating and terminating exchanges will differ greatly in length and direction according to the position of the exchanges in the network.

In order to select widely differing paths in response to the same code letters, the said letters are normally dialled into a register translator at the originating exchange; the register translators at the different exchanges are differently arranged so that in response to the same code letters they transmit the routing digits necessary for the particular path from the originating to the terminating exchange; these routing digits may differ in number as well as in value from the code digits dialled. It is generally unnecessary, from a technical point of view, for the numerical digits to be stored, but owing to the delay caused by the storage and retransmission of the code digits, the numerical digits are usually dialled before the terminating exchange is ready to receive them, so that it is necessary to store these digits

and retransmit after the inter-exchange route is complete. If, however, the selection of the terminating exchange can be completed, under direct control of the calling party for instance, before the numerical digits are dialled, it is no longer necessary in normal cases to store the numerical digits. 55

According to one feature of the present invention, the selection of the numerical portion of certain inter-exchange connections is performed under direct control of the calling party. 60

The register translators are very complete in structure and in consequence their cost is high. Any modification of the present arrangements whereby the number of translators to be provided was substantially decreased would therefore result in a substantial reduction in the cost of installing automatic exchanges in large networks, apart 70 from any advantages or economy in operation which might be introduced. 65

The provision of junctions outgoing from a particular exchange in a network for inter-exchange communication is based on the traffic density to the other exchanges in the network. Direct junctions are provided between the said exchange and others to which the traffic is great, while the traffic to exchanges, the number of calls to which is small, 80 is passed indirectly thereto over two or more junctions via one or more intermediate or tandem exchanges. It has been found by a study of the traffic conditions in the London area, that the tandem traffic from an exchange is hardly ever more than 10% of the total traffic outgoing from the exchange. It 85 will be seen therefore, that if calls to exchanges directly connected to the originating exchange could be set up independently of the register translators, the number of register translators to be provided in the said exchange would be greatly reduced. 90

The main feature of the present invention consists therefore, in a circuit arrangement for an automatic or semi-automatic telephone exchange system comprising register translators, characterized in this that certain inter-exchange calls are completely set up under direct control of the calling party. 95 100

It is well known that of a group of trunks or junctions provided for dealing with a certain volume of traffic, the traffic which actually passes over the last 20% or 30% of said lines, (according to the size of the group) is usually not more than 1% of the total traffic. It is proposed, therefore, in the network described above, to provide 70% to 80% only of the junctions to directly connected exchanges necessary to carry the total traffic between the exchanges, and to provide alternative trunking via tandem junctions for the 1% say of traffic to the said exchanges for which junctions are not provided. By so doing, one additional tandem junction can replace a large number of said direct junctions owing to the small amount of traffic which the latter would carry, and the large number of tandem junctions over which the additional calls will be distributed.

It will be appreciated that the volume of traffic in the various interexchange junction groups varies considerably from time to time, due to extensions and the introduction of new exchanges. By the method of alternative trunking which is proposed these traffic variations may be handled by adjustment to the one group of junctions leading to the tandem exchange without interfering with every individual group.

It should be understood that calls which have available this alternative routing facility may normally be connected by means of direct junctions without any element of translation and it is only when all the direct junctions have been tested and found to be engaged, that the translators are brought into use. It follows, therefore, that the code switches forming part of the translators have a single set of translating terminals only for each exchange.

According to another feature of the invention a circuit arrangement for connecting one exchange to a plurality of other exchanges comprises a plurality of groups of outgoing junctions, and means whereby a modification in the size of one of said groups will satisfy a change of traffic intensity over any one or more of said junction groups.

Since tandemed connections are to be set up under control of a register translator, according to a further feature of the invention, calls to certain exchanges are adapted to be set up either under complete control of the calling party or by the aid of a register translator.

According to yet another feature of the invention, calls from one exchange to another may be set up over a plurality of junctions, over certain of which calls to further exchange or further exchanges may also be set up.

If certain junctions outgoing from an automatic exchange lead to manual exchanges provided with coder call indicators, it is

necessary to translate the numerical impulses into coded impulses at some stage in the connection. It is not, however, necessary to store and translate the dialled code digits since direct junctions are selected under direct control of the calling party.

The register translators may therefore be arranged in such a way that they are adapted to store and retransmit both code and numerical digits or numerical digits only. In certain types of automatic telephone systems, for instance the controller bye-path system, the inter-exchange junctions are not directly connected to the incoming selectors, and there is an interval after a junction has been seized at its outgoing end before the incoming exchange is ready to receive the next train of impulses. It is possible in such arrangements that the first numerical digit may be dialled before the incoming exchange is ready to receive it. In order to deal with this possibility, a signal may be sent back when the incoming exchange is ready, and if the first numerical digit is dialled before the receipt of this signal at the originating exchange, the numerical digits may be routed to a register translator: retransmission being dependent on the receipt of said signal.

According to yet another feature of the invention, therefore, a register translator is taken into use under certain circumstances during the setting up of a connection via a route over which the connection is normally completed under direct control of the calling party.

Due to the fact that in a number of calls, there is not sufficient time to connect up a register translator after it has been determined that a register translator is required in setting up the connection, it is proposed to connect up a register translator before discrimination takes place for all inter-exchange calls, and to release it unused if the call is completed under direct control of the calling party.

According to a further feature of the invention therefore a register translator is taken into use during the setting up of an inter-exchange connection, and if the call is to be completed under direct control of the calling party the register translator is released unused.

It will be noted that, according to the present proposals, the register translators are set in accordance with the value of the code digits for tandemed connections only.

The invention will be described with reference to a controller bye-path exchange, in which the first selector stage operates in response to the first code digit to select a second code bye-path circuit and conversational switch. Each second code bye-path circuit comprises a switch which is adapted to be set by the second and third code digits; this switch controls the selection of a junction

outgoing from the bye-path switch in the required direction, determines in certain cases whether a register-translator is required, and stores the second and third code digits for retransmission to the register-translator if taken into use.

According to another feature of the invention the register-translators are each associated in common with a plurality of discriminating circuits, each of which is in turn associated in common with a plurality of talking circuits, the discriminating circuits being adapted to determine whether or no a register-translator is to be used in setting up a connection.

The alternative trunking feature described may be extended. Thus, register-translators and discriminating bye-path circuits may be provided at a tandem exchange and if the direct junctions from a tandem exchange to a terminating exchange are all busy, a register-translator may be taken into use, and control the selection of a route via a further tandem exchange in response to one or more of the routing digits sent out from the first exchange.

The invention will be better understood from the following description taken in conjunction with the accompanying drawings in which:—

Fig. 1, is a general diagram illustrating an arrangement according to the invention as applied to the controller bye path system.

Figs. 2A and 2B, 3A and 3B together constitute a circuit diagram of the second bye-path common control circuit and an associated second path switch, indicated respectively at SB and S2 in Fig. 1. The leads at the right hand side of Figs. 2A and 2B join the corresponding leads at the left hand side of the Figs. 3A and 3B.

Figs. 4A and 4B together illustrate the circuit diagram of the register translator such as RT shown in Fig. 1.

Fig. 5, is a circuit diagram of a repeater to a tandem exchange.

Fig. 6, shows the wiring of connections between certain bank contacts of the switches R3 and R2 in the second bye path SB shown in Fig. 1.

The general principle of operation will now be described with reference to Figure 1 of the accompanying drawings which show the layout of the apparatus used in one embodiment of the invention for setting up the various types of calls.

A subscriber S originating a call operates the usual line relay which extends a start signal to the first bye-path FB causing it to make connection by means of the associating switch PF with a free first path S1 tied to a second line finder LF2 which is caused to rotate to find a free first line finder LF1 having access to the calling line. It should be understood that this start signal is connected

to a number of first bye-paths such as FB which will make connection with other free paths and line finders. The first digit causes a selective operation on the part of the first bye-path which tests for a free second path and second bye-path. The second digit is received by the switch R1 of the second bye-path SB and is stored by the switch R3 under the control of the switch R1. The third digit is stored in the switch R3. The switch R2 selects the required group under the control of R3 and then searches for a free outlet in that group through one of the repeaters such as TR, CR or DR or alternatively selects a free switch in the succeeding local switching stage. During the time that the switch R3 is receiving the third digit a starting signal is extended to a number of register translators such as RT which cause their various associating switches RF to search for the calling second bye-path. If the call is to be tandemed the impulsing circuit will be relayed from the second bye-path SB to the register translator which will store the numerical impulses and at the same time a preliminary translation depending upon the setting of R3 will be sent to the code switch C which has already been partly positioned under the control of the associating switch RF, the setting of which corresponds to the value of the A-digit. As soon as the code switch has been set the translated code will be sent from the sender through the associating switch RF and the switch R2 of the second bye-path to the tandem exchange.

When all the impulses have been sent the transmission bridge located in the tandem repeater TR is introduced and the connection set up through the switch S2, the second bye-path SB and the register translator RT being released.

In the case of a call to a call indicator exchange the register translator is introduced as before, but the code switch C is not used. When all the numerical impulses have been stored a signal is passed through the switch RF the switch R2 and the repeater CR to the manual exchange which makes a return signal when the sending can commence. After the sending is completed the transmission bridge in the repeater CR is introduced and the connection established through the switch S2, the bye-path SB and the register translator being released.

In the case of a call to be handled over a direct junction, the register translator RT will become associated with the second bye-path SB but will be released as soon as a connection is established over the switch R2 to the distant exchange. If all the junctions to the distant exchange are found to be engaged the succeeding digits will be relayed to the register translator and the switch R2 will be moved forward to the group of outlets leading to the tandem exchange. The

- code switch C of the translator will be operated as already explained for the call through the tandem exchange and the sending will be carried out in a similar manner.
- 5 Should it happen when the switch R2 selects a free direct junction, that the distant exchange is not ready to accept the call when the calling subscriber commences to send the numerical impulses, due, for instance,
- 10 to the presence of non-numerical switching between the junctions and the incoming selectors, the impulses will be relayed to the register translator and transmitted to the distant exchange as soon as it becomes ready.
- 15 Local calls will be established through the switch R2 of the second bye-path but in this case there will be no facility for passing the call to the register translator if all outlets are busy.
- 20 Calls routed through the tandem repeater TR will be classified by means of a metering signal originated by the code switch C of the register translator and passed through the associating switch RF, and the switch R2 of
- 25 the second bye-path to the repeater TR.

From the description above it will be seen that the selection at the outgoing selector stage is always performed independently of the register-translator. According to another feature of the invention therefore an outgoing junction is taken into use during the setting up of an inter-exchange connection independently of the register translator.

A further feature consists in this that in setting up inter-exchange calls with the aid of a register translator, the register translator does not exercise control of the setting up of a connection until a junction outgoing from the originating exchange has been seized.

The particular embodiment of the invention will now be described in detail with reference to the remaining figures of the accompanying drawings which illustrate the detail circuits of the arrangement shown in Fig. 1, the switch RM1, RM2, and RM3 in these figures corresponding respectively to the switches R1, R2 and R3 of Fig. 1.

The second bye-path SB is tested from the first bye-path FB over a circuit extending via conductor T (Fig. 3A), contacts hs1, tt1, the home position of the wiper rm19, contacts be4, the wiper and home position rm22 to test battery. The impulsive leads (Fig. 3B) are extended through the contacts c17, hh6, to one winding of the relay A and ground, and through contacts c18 and hh7 to the other winding of relay A and battery. Relay A closes the obvious circuit for relay B at a1 (Fig. 3A). Relay B closes the obvious circuit for the relay BE via contacts c19 and b1. Relay BE closes at be1 ground to the test wire and removes the test battery at be4. Contact be3 prepares the impulsive circuit of the switch RM1, the first series of impulses

being received by the switch RM1 through contacts e4, be3, winding of the relay C, contacts a1, to ground. Relays B and C are of the slow releasing type and remain operated during the train of impulses. When the switch RM1 reaches position 2 a circuit is formed from ground at contacts b1 through the contacts e7, wiper rm19 and the second bank contact and the home position and wiper rm29 to the magnet RM2 and at the same time through the home position and wiper rm35 to the magnet RM3 (Fig. 2A) through its own interrupter springs. When RM3 steps off-normal, an alternative stepping circuit is formed from earth via e1, n1, off-normal bank and wiper rm35 to RM3 through its interrupter springs. The bank contacts of the wiper rm18 are wired in pairs to the contacts of the wiper rm38 so that the wiper rm18 when in positions 2 and 3 is in contact with position 2 of the wiper rm38 and when the wiper rm18 is in positions 4 and 5 it will be connected to the wiper rm38 in position 12 and so on. In consequence when the switch RM3 reaches position 2 a circuit is completed for the relay N from battery, winding of relay N through wiper and bank contact rm38 to the bank contact and wiper rm18, contacts tt5, contacts r4 to ground. Relay N opens at n1 the driving circuit for the switch RM3 which remains in position 2 until the switch RM1 passes to position 4 after which the switch RM3 steps to position 12 where the circuit for the relay N is again closed. The bank contacts associated with the wipers rm31 and rm32 are wired to the bank contacts associated with the wiper rm20 as shown in Fig. 6 in such a way that each position on the bank of the switch RM3 which represents an exchange is connected to the first of a group of contacts associated with the wiper rm20, the remaining contacts on the banks rm31 and rm32 being multiplied to the exchange terminals immediately following so that as soon as switch RM3 passes one set to multiplied terminals marking a group in the bank of rm20 it will immediately make contact with the next set to mark the next group so that marking is applied continuously to the bank rm20 and switch RM2 cannot overrun switch RM3. Wiper rm32 is earthed throughout the reception of the second code digit, via d2, e8, so that the intermittent operation of ja3 is without effect.

When the switch RM3 takes its first step the wiper rm20 will make contact with the multiple extending to the first set of exchange contacts which will be wired to the beginning of the first group of outlets of the switch RM2 and a circuit will be established for the relay M through contacts h9, wiper rm20, the wiper rm31, contacts ja3, d2, r8 to ground. The relay M will open the driving circuit of the magnet RM2 established through its interrupter springs, the off normal bank of the

wiper rm_{29} contacts $h4, m1, q1, p1, h5$ to ground. When the switch RM3 passes the first exchange multiple the circuit for the relay M will be opened and the switch RM2 will commence to drive until it reaches the commencement of the next group marked by the wiper rm_{32} , in which position the relay M will reoperate reopening the circuit of the magnet RM2. When the impulsing is completed the relay C will release and when both relays M and N are operated a circuit will be completed for the relay E from battery, through contacts $n2, c3, m1, q1, p1, h5$ to ground. Relay E closes a locking circuit through contacts $e5$ to ground at b_{e2} . Contacts $e1$ open the driving circuit of the magnet RM3. Contacts $e3$ extend the impulsing circuit to the magnet RM3, contacts $e4$, complete a driving circuit for the switch RM1 through contacts $t1$ and the interrupter springs to ground and contacts $e8$ open so that if JA is operated M falls back, and switch RM2 again steps on. A circuit was established for the relay JA while the switch RM1 was in positions 3, 5, 7, 9 and 11 and if the switch RM1 remains in one of these positions relay JA locks up through contacts $ja5$ and $e7$ to ground at $b1$. The switch RM1 will hunt for the selected path switch SM (Fig. 3A corresponding to S2 of Fig. 1) testing from battery through the relay T and the non-inductive resistance over wiper rm_{12} for ground on the hold wire. Relay T in operating opens the driving circuit at $t1$ closing the obvious circuit for the relay TT. Relay TT opens at $tt1$ the ground on the test wire and connects it to the relay T and the removal of this ground allows the release of the preceding bye-path. The contacts $tt2$ and $tt3$ complete the impulsing circuit independently of the preceding bye-path. The third set of impulses are stored over the following circuit:—battery, winding of the magnet RM3, $g2, h1, ci4, e3, be3$, winding of relay C, $a1$ to ground. When the relay C reoperates a circuit is closed for the relay CE from battery through contacts $e2, ci3, c1, b1$ to ground. Relay CE locks through contacts $ce8, r1, ci2$, to ground. The operation of the relay CE closes the start signal to the register translators from ground at $k1$ through contacts $ce1$. It also closes a testing circuit from the terminal T (Fig. 2B) through contacts $g1, ce2, k2$, to non-inductive winding of relay K. When the third code digit is complete and the relay C releases a circuit will be established for the relay TM (Fig. 2A) from battery, through contacts $c1, ci3, ce8, r1, ci2$, to ground at $b1$. At $tm2$ a ground will be extended through contacts $j2$ and wiper rm_{36} or rm_{37} to the selected exchange terminal. The exchange terminals in the banks of rm_{36} , rm_{37} , are connected via a distributing frame DF to one of a number of terminals AT, D, C1, DC, and S. If the terminal on which

the selected wiper rm_{36} or rm_{37} has come to rest does not represent any exchange the ground will be extended to the DC terminal causing the operation of relay G (Fig. 3B). Contacts $g1$ will open the testing circuit to the register translators, causing the operation of the relay K through the contacts $ce2$. Relay K will open at $k1$ the start signal to the register translators. Contacts $g6$ and $ce7$ will connect number unobtainable tone to the line from lead NU (Fig. 3B). The contacts $tm1$ extend a ground through the contacts $ja4$ to the wipers rm_{39} or rm_{30} in the banks of which each contact individual to an exchange is connected to a meter common to a number of control circuits which totals the number of calls to the particular exchange. A single common meter may be provided for all dead codes.

If the selected wiper rm_{36} or rm_{37} rests at the end of the third code digit on the local terminal, a connection will be completed from ground, contacts $tm2, ja1$, through DF and the S terminal to the relay N and battery, and when the relay C releases a circuit will be closed for the relay R (Fig. 3B) from battery, winding of relay R, contacts $r3, ce4, n2, c3, m1, q1, p1, h5$ to ground. The fact that the relay M is operated indicates that the switch RM2 is standing on the first contact of the group marked from the wiper rm_{31} (or rm_{32}) and relay R locks through contacts $r3, at5, h7, e7$ to ground at $b1$. The operation of relay R opens the circuit of the relay M at $r8$ causing the driving circuit of the magnet RM2 to be reclosed, opens the circuit of CE at $r1$ and closes at $r6$ and $r7$ the test circuit for the relays Q and P. The switch has two sets of wipers, and tests two outlets at a time through wipers rm_{23}, rm_{24} . The contacts $r1$ open the locking circuit of the relay CE and of the relay TM both of which now commence to release.

If all the outlets are engaged the switch RM2 continues stepping until it reaches the last set of outlets for the group where a circuit will be completed for the relay M through contact $h9$, wiper rm_{20} , contacts $r8$ to ground. The operation of relay M closes a circuit for the relay G (Fig. 3B) through contacts $r2, e6, m1, q1, p1, h5$ to ground. Relay G opens the testing circuits of the relays P and Q at $g5$ and $g7$. At $g1$ a locking circuit is provided for the relay K through contacts $k2, hh1$. The opening of the back contact at $g1$ releases the register translator. Contacts $g2$ open the impulsing circuit thereby preventing the switch RM3 from taking any further steps. The contacts $g6$ provide busy tone through the tone condenser, contacts $ce7$ and contacts $r5$ from the lead BT (Fig. 3B). When the calling subscriber releases the relay A opens the circuit of the relay B and all switches return home.

If a free outlet is found and the relay Q

operates from battery at the succeeding switching stage through the wiper *rm24*, contacts *r6, g7*, winding of relay *Q* to ground at *b1*; relay *Q* will open at *q1* the driving circuit of the switch *RM2* and close a circuit for the relay *J* through *q1, p1, h5* to ground. Relay *J* closes at *j1* a circuit for the relay *H* which will close contacts *h6* to provide a locking circuit for itself and relay *J* from ground at *be2*. If wiper *rm23* had found first, relay *P* only would have operated, followed by relay *H* only relay *P* being in turn short-circuited. The operation of contacts *h7* and *j3* places ground on the wiper *rm24* 15 short circuiting relay *Q* which releases; the connection of direct ground to wiper *rm24* initiates operations in the outgoing repeater as described later. The driving circuit for the switch *RM2* is now opened by the contact *h4*, and the circuit for relay *R* is opened at contacts *h7*. The following driving circuit is closed; battery and magnet *SM* of the path switch, bank contact and wiper *rm17*, contacts *h4, m1, q1, p1, tt5*, wiper *rm18*, to the 20 interrupter springs of the magnet and ground. A marking multiple between the path switch and the switch *RM2* causes the operation of the relay *M* through contacts *h9, j2*, wiper *rm22*, the marking multiple, wiper *sm4*, the wiper *rm10*, contacts *h10* and *r8* to ground. Relay *M* closes a circuit for the relay *G* through contacts *c15, hh9, e6, m1, q1, p1, tt5* to ground through the wiper *rm18*. The effect of the operation of relay *G* at this 25 time will be explained later. The operation of relay *H* closes at *h8* a circuit for the relay *DH* from the wiper *rm26*, contacts *j4, hh6*, winding of the relay *DH*, *h8, j5* and wiper *rm28*. The succeeding control switch will return 30 a feed immediately to cause the operation of the relay *DH* which closes at *dh1* the following circuit for the relay *HH* (Fig. 2B); battery and winding of relay *HH*, contacts *dh1, c2, h3*, to ground. Relay *HH* locks through contacts *hh5* and *h6* to ground at *be2*. The operation of the relay *HH* opens at *hh1* the holding circuit to the register translator and at *hh3* it opens the extension of the impulsive circuit closed by the contacts *h2*. Contacts *hh4* open the circuit of the relay *DC*. Contacts *hh6* and *hh7* open the circuit of the relay *A* and extend the subscriber's loop to the succeeding bye-path disconnecting the relay *DH* which now releases. Subsequent impulses are transmitted to the succeeding bye-path without causing any further operation to the bye-path *SB*. The opening of the circuit of the relay *A* opens in turn the circuit for the relay *B* and 45 the operating circuit of the relay *BE* which is retained, however, from ground on the test wiper *rm24*, contacts *j3, h7, e7, ci9*, to the relay *BE*. The operation of the relay *G* already described closes a circuit for the relay *HS* from battery, winding of relay *HS*, wiper *rm16*, contacts *tt4*, non-inductive resistance, contacts *hh8, g3, h6, be2* to ground. The relay *HS* extends a subscriber's loop through contacts *hs3* and *hs4* to wiper *sm1, sm2*. It opens at *hs2* the hold the circuit which is transferred to the wiper *sm3* and the contacts *hs5*. The succeeding bye-path having received a set of impulses will cause its *R1* switch to hunt round to make association with the path, testing over the hold wire for ground. The ground fed to the wiper *sm3* through the contacts *hs5*, wiper *RM16, tt4, hh8, g3, h6* and *be2* will cause the association to be completed and an impulsive circuit to be established through that 50 associating switch. The ground fed back from the succeeding bye-path will be removed from the wiper *rm24* and the relay *BE* will release. Contacts *be1* will open the circuit for the relay *T* and the relay *T* will open the circuit of the relay *TT*. The contacts *be2* will open the circuit of the relays *E, J* and *H* and *HH*. Relay *M* will release due to the release of relays *H* and *J*. Relay *G* will release due to the release of relays *E* and *M* the homing circuit for the magnet *RM2* is established through its interrupter springs wiper *rm29* contacts *h4, m1, q1, p1, h5* to ground. The homing circuit for the switch *RM1* is established through contacts *e4, be3, wiper rm15, contacts t1, interrupter springs and ground*. The homing circuit for the switch *RM3* is established through its interrupter springs, the wiper and off normal bank *rm35*, contacts *n1, e1* to ground. When the switches *RM1* and *RM2* have returned to their home positions the testing circuit for the bye-path is re-established. 55 If the switch *RM3* is standing at the end of the third code digit on a set of terminals representing another exchange reached over direct junctions, ground extended from the contacts *tm2* will be jumpered to terminal *S* causing the operation of the relays *N* and *R* as already described for the local call. It may happen that although a junction is found free the bye-path at the incoming end is not immediately available and in consequence relay *DH* does not operate due to the resistance with which it is in series; this 60 resistance is located at the outgoing repeater. When the bye-path at the incoming end becomes free the resistance in the junction is reduced and a relay in the repeater operates removing the resistance from the circuit of the relay *DH*. The subsequent operation is similar to the local call unless the relay *DH* fails to operate before the next train of impulses commences in which case a circuit is completed for the relay *DC* through contacts *hh4, c2, h3* to ground. Relay *DC* locks through contacts *dc3, h6* to ground at *be2*. Contacts *dc1* close the obvious circuit for the relay *CI* which locks through contacts *ci2*, to ground at *b1*. The relay *CI* provides an 65 70 75 80 85 90 95 100 105 110 115 120 125 130

operating circuit for the relay CE through contacts c_2 , c_3 , g_4 to ground at b_1 , and disconnects TM at c_3 . The operation of the relay CE maintains at c_2 the circuit for the relay K to the register translator. The first train of numerical impulses is transmitted through the contacts a_1 , through the winding of C, b_3 , e_3 , h_2 , h_3 to the pulse wire to the register translator. The operation of contacts c_4 , provide an alternative impulse path which is established before the possible operation of the relay HH. At the end of the first numerical digit the relay C releases and provides a further chance for the relay HH to operate through contacts d_1 , c_2 and h_3 to ground. If the relay HH operates ground is extended through t_3 , h_2 , h_3 , d_2 to the DC lead to the register translator indicating to that circuit that sending may commence. Contacts c_7 , c_8 maintain the circuit from relay A over the subscriber's loop independent of the contacts h_6 , h_7 and when the relay HH operates the circuit to the distant exchange is extended over contacts h_6 and h_7 to the positive and negative leads to the register translator. As in the case of the local call the path switch SM will be positioned by the marking multiple, relay M operating over the contacts h_9 , j_2 , as already described. The circuit for the relay G cannot, however, be completed as the contacts c_5 are opened and the contacts r_2 are also opened due to the fact that the relay R released when relay H operated. When the register translator has transmitted the thousands, hundreds, tens and units impulses a ground is extended to the K wire causing the operation of relay G and causing the operation of the relay HS. The operation of relay G opens the circuit of the relay CE at g_4 and the locking circuit of the relay BE previously extended through the contacts c_9 and c_5 to ground at b_1 is opened when the contacts c_5 return to normal. The release of relay BE opens the circuit for the relays T and TT and also the relays E, J, H and HH. Contacts t_2 and t_3 open the circuit of relay A which opens the circuit of the relay B causing the release of the bye-path and the register translator.

If the switch RM3 is standing on a set of terminals at the end of the third code digit representing an exchange to which connection is established either over direct junctions or by means of tandem junctions, the ground from contacts t_2 , j_1 will be extended to the terminal AT causing the operation of relay AT which locks through contacts a_2 , h_7 , e_7 to ground at b_1 . Contacts a_1 close the obvious circuit for the relay N. Relay N causes the operation of the relay R as already explained, relay R locking through contacts r_3 , a_5 , c_6 , h_7 , e_7 to ground at b_1 . If a free outlet is found the call is extended as already explained, contacts h_7

opening the circuit for the relay AT. If the relay DH fails to operate in time the connection is set up by the register translator as already explained. If all the outlets are busy the operation of the relay G closes at g_4 the circuit for the relay D through contacts a_4 . Contacts d_3 cause the operation of the relay CI and both relays lock through contacts c_2 , to ground at b_1 . The circuit for relay TM is opened at c_3 and TM releases. Contacts a_3 extend the circuit to the register translator which would otherwise be opened at the contacts g_1 . Contacts c_4 extend the impulsing circuit to the register translator and contacts c_7 and c_8 prepare the permanent circuit for the relay A. Contacts d_2 open the marking circuit for the relay M and close an individual marking circuit to the first outlet of the junctions leading to the tandem exchange which will always appear as the last choices on the bank of the switch RM2. The operation of the contacts c_6 open the circuit of the relay R and in consequence the relays P and Q are not testing while the switch RM2 is moving forward. The opening of the contacts m_1 opens the circuit for the relay G. When the switch RM2 reaches the first outlet to the tandem exchange relay M reoperates and as the relay CE has reoperated through the contacts e_2 , c_3 , g_4 to ground at b_1 , the circuit is completed for the relay R through contacts c_4 , n_2 , c_3 , m_1 , g_1 , p_1 , h_5 to ground. Relay R now locks through contacts r_3 , a_5 , c_6 , h_7 , e_7 , to ground at b_1 . Contacts r_8 open the circuit of relay M causing the switch rm2 to step forward testing for a free junction. The subsequent operation of the relays H and HH has already been described. The operation of relay HH extends ground from t_3 through contacts h_2 , h_3 , d_2 , d_4 to the D lead to the register translator causing the latter to initiate the setting of the code switch which will be described in detail later. The contacts of the banks corresponding to the wipers $rm33$ and $rm34$ are multiplied together to effect the primary translation of the code in the following manner. The translator switch in the register controller is stepped forward while ground impulses are sent to the switch RM3 therefrom. The stepping of the translator switch is dependent on the completion of a circuit over wiper $rm33$ or $rm34$. The contact corresponding to a particular exchange is therefore multiplied to a number of contacts to the left thereof in Fig. 2B equal to the number of steps that the translator switch is required to take to reach the corresponding setting. Ground is extended from the register translator over the S lead through contacts j_2 , the wiper and bank contact $rm33$ or $rm34$ contacts d_1 to the magnet RM3 causing the magnet to step. The stepping of the magnet RM3 is continued until the wipers

130

step off the multiple, the preliminary translation being equal to the number of steps made by the switch RM3. When all the impulses have been transmitted from the register translator a ground is extended over the lead to operate the relay G. The contacts g_3 complete a circuit for the relay HS as already described.

- If the terminals on which the switch RM3 is resting after the third code digit corresponds to a call indicator exchange the ground from contacts tm_2 and ja_1 will be extended to the CI terminal causing the operation of the relay CI which locks as before. Contacts ci_1 close the obvious circuit for the relay N causing the subsequent operation of relay R as already explained. The contacts ci_3 maintain the circuit for the relay CE and break the circuit for relay TM, which releases. The contacts ci_8 and ci_7 maintain the circuit for the relay A independent of the contacts hh_6 and hh_7 . The contacts ci_{10} prepare a circuit for the relay HH independently of the relay DH. When a free junction is found the relay P or Q is operated resulting in the operation of the relay H or the relays H and J and ground is extended through contacts be_2 , h_6 , dc_3 , d_5 , ci_{10} to operate the relay HH which locks through contacts hh_5 . The impulsing circuit is completed through contacts ci_4 to the pulse lead to the register translator. The register translator is not adapted to send more than the four numerical digits to a call indicator exchange and in consequence the second bye-path does not in this case send a preliminary translation to the register translator. Ground from contacts tm_3 is extended through contacts hh_2 , k_3 , dc_2 , d_4 to the CI lead to the register translator. When all the impulses have been sent from the register translator ground is connected to the K lead to operate relay G causing the cut through and release as already explained.
- If the terminals on which the switch RM3 is resting after the third code digit is only connected over tandem trunks, ground extended from contacts tm_2 and ja_1 will be jumpered to the D terminal causing the operation of relay D which by closing its contacts d_3 causes the operation of the relay CI, both relays locking over ci_2 to ground at b_1 . Contacts d_2 switch the marking connection from the wiper rm_{31} (or 32) to the commencement of the tandem group causing the RM2 switch to run forward until checked by the relay M at the commencement of the group of tandem outlets. Contacts ci_1 close the obvious circuit for relay N and when both relays N and M are operated a circuit is closed for the relay R. The operation of relay R causes the switch RM2 to test within the chosen group. When a free trunk is found the relay H is operated as already explained and a circuit is prepared for the re-

lay DH. The impulsing circuit has, however, been extended to the register translator through the contacts ci_4 . When the relay DH operates a circuit is completed for the relay HH and an indication is sent to the register from ground at contacts tm_3 , hh_2 , k_3 , dc_2 , d_4 to the D lead. Subsequently the register translator will proceed with the preliminary translation causing the switch RM3 to step forward until the wiper rm_{33} or rm_{34} leaves the multiple connected to the magnet. When the register translator has finished sending ground is extended to the K lead causing the operation of relay G and the switching and releasing operations are carried out as already explained. Should it happen that all the tandem outlets are engaged relay G will be operated on the last set of outlets introducing busy tone through contacts g_6 , ce_7 and r_5 . The operation of the contacts g_1 causes the release of the register translator.

The register translator shown in Figs. 4A and 4B is capable of searching over a number of second bye-paths such as SB. It will be understood that the wipers rf_1 — rf_0 of the switch RF cooperate with the bank contacts T, S, K, P, etc. shown in Fig. 2B. The second bye-paths are divided into groups depending upon the first digit dialled by the subscriber and it is intended that the plurality of register translators shall have access to second bye-paths in a plurality of groups. All the register translators having access to one numerical group of second bye-paths will attempt to make connection as soon as a calling signal is received. A calling signal will cause the operation of the relay A in each register translator which is free, from battery winding of the relay A, the home contact and wiper ns_4 , wiper and home contact ns_7 , the common start lead, ce_1 , k_1 , to earth. The relay A closes a driving circuit for the finder switch RF through its interrupter springs, contact a_3 , the home contact and wiper sm_3 of the sender switch the home contact and wiper ns_2 , to ground at b_1 . At the same time a testing circuit is prepared from ground, contacts a_4 , winding of relay B to the test wiper rf_2 leading to the test lead T in Fig. 2B. When the switch RF finds a bye-path in a calling condition the relay B will operate opening at b_1 the driving circuit of the finder switch and closing at the same contacts a locking circuit for the relay B. Contacts b_2 prepare a circuit for the relays H, J of LN. Contacts b_3 place a short circuit across one winding of the relay H and contacts b_4 prepare the impulsing circuit for the numerical switch NS. When the register translator makes connection with the second bye-path it does not know initially what type of call is being made but a ground discriminating signal is sent over one of the leads, D, CI or DC associated with the wipers

90

95

100

105

110

115

120

125

130

rf8, rf7 and rf6 indicating translation, code sending and numerical sending only, respectively. The connection of discriminating earth is dependent on relay TM in the second bye-path being deenergized and relay HH being energized and relay HH being energized, and the particular wiper to which the earth is connected is determined by the condition of relays D and DC. For calls to be tandemed, D only is operated, for C.C.I. calls neither relay is operated, while for numerical sending only DC is operated. If the ground is extended to the wiper rf8 for calls through tandem relay H (Fig. 4A) operates alone. The relay H closes the circuit for the magnet of the code switch CM through its interrupter springs, contacts ca2, bb3, h1, to ground and at the same time a ground is extended through the contacts j4 and h2 to the wiper cm5 of the code switch which tests to find the set of contacts cross connected to the wiper rf4 of the finder switch which is connected to the relay CA through contacts ln2. All the positions on the bank of the finder switch associated with wiper rf4 which lead to the same group of second bye-paths which, as already explained, are characterized by the first digit dialled, will be connected together and to one home position on the code switch and in consequence the code switch will have one home position for each group of second bye-paths to which the register translator has access. In general the positions between the home positions will be allocated to exchange designations which have the same first code letter. The actual position on the code switch is set by advancing from the home position in accordance with the preliminary translation. If one group becomes congested there is no technical reason why the preliminary translation described below should not advance the code switch into the group of contacts allocated for another group of second bye-paths, the number of steps to be taken by the code switch being entirely arbitrary and determined only by the number of contacts in banks rm33 or rm34 which are multiplied to the contact therein individual to the particular exchange designation. When the code switch reaches the home position indicating the group with which the finder switch RF is associated, the circuit will be completed for the relay CA which will operate opening at ca2 the driving circuit and closing a circuit via ej1, ca2, bb3 and b1 for the relay BB which will operate locking through contacts bb3. The same ground is extended to wiper sm1, home position, contacts cb2, j1, ss2, winding of relay CC to battery, but there is a possible short circuit through contacts cc1, cb1 and the interrupter springs ms1 to the same ground. As a result the relay CC will not operate unless the interrupter springs are open. When CC operates a circuit is completed for the relay CB

through contacts cc3, ca1, ln1, bb3, to ground at h1. Contacts cc2 provide a locking ground for CC through contacts cc1 independent of the contacts cb2. Contacts cb1 extend the impulse springs through relay CZ to the wiper rf3 which is connected to the S lead to the second code bye-path and when the interrupter springs are closed an impulse will be sent to switch RM3 in the second bye-path. The operation of relay CZ will provide an alternative circuit for the relay CB through contact cc1. CB is of the slow to release type and remains operated so long as impulses are being sent through the relay CZ. Contacts cc2 impulse the magnet CM of the code switch causing that switch to advance its wipers one step for each impulse sent to the magnet RM3. After the switch CM has taken one step the circuit for the relay CA is opened and it releases but due to the operation of contacts bb3, the code switch magnet CM does not get a renewed circuit. When RM3 in the second bye-path has stepped off the multiple indicating the preliminary translation, there will be no circuit for the relay CZ and after a period the relay CB will release. The circuit for the relay CC was opened when the relay CZ is operated on the first impulse and when the relay CB releases a circuit will be reclosed through contacts cb2, j1 and ss2 but as before relay CC will not operate until the interrupter springs are opened. When relay CC reoperates it again locks through contacts cc2 and cc1 to ground at h1 but as the relay CA has now released there is no circuit for the relay CB and when the interrupter springs remake the ground is extended through contacts cb1 and cc1 to the sender switch SM. The sender switch makes one step and in position 2 a circuit is closed for the relay SA through contacts j2, second bank contact and wiper sm1 to ground at h1. Relay SA opens at ss2 the short circuit across the negative and positive lines which are now only connected by means of the pulse springs LS which open once for every impulse sent to the magnet SM. The contacts in the banks of wipers cm1—cm4 which correspond to the various exchanges to be reached via tandem are jumpered to the required contacts 3—12, 14—23, 25—34, and 26—35 in the bank of wiper sm2. When the required number of impulses have been sent according to the translation switch SM will be in any one of positions 3—12 and ground is extended through the contacts j4, h2, wipers cm1 and sm2, contacts ss1 to the relay SZ and battery. Relay SZ locks through contacts ss1 and sa1. Contacts ss5 replace the short circuit across the loop springs LS, and contacts ss4 provide a driving circuit for the switch SM through its interrupter springs, ss4, j2, to the bank contacts and wiper sm1 which is still connected to ground at h1. In this way the sender switch drives to position 13 where the circuit

for the relay SA and the magnet SM is opened. The operation of contacts $ss2$ open the circuit for the relay CC which has, therefore, been released. The relay SA is of the slow 5 to release type and falls back slowly. The relay SZ also falls back slowly after the release of relay SA. When the relay SZ releases, the circuit for the relay CC is reclosed and the sequence of operations is repeated except that the relay SZ is operated over a 10 jumper between one of the bank contacts associated with the wiper $cm2$ of the code switch and one of contacts 14-23 of $sm2$. Relay CC is again reoperated in position 25 and the relay SZ operated from one of the 15 jumpers associated with the wiper $cm3$ of the code switch. If there is a fourth translated digit this will be obtained in the same way from the wiper CM4 of the code switch but 20 should there be no fourth translated digit, wiper CM4 will be connected through its bank contact to the CO terminal which is wired to the bank contact No. 37 associated with the wiper $sm2$. This ground will be 25 extended through the wiper SM2 and the contacts $ss3$ to the magnet SM and to the relay SA causing the sender switch to advance immediately to position 49 and preventing release of relays SA and SZ in position 37. If 30 it is required to send only one translated digit the corresponding contacts in the banks of wipers $cm2$, and $cm3$ and $cm4$ will be jumped to the CO terminals numbers 13, 25, 37 respectively by which means the sender switch will advance to position 49 after the 35 first digit has been set.

During the time that the code switch has been set and the translated digits have been sent the numerical impulses have been received and may be retransmitted. The impulsive circuit for the numerical switch NS, contacts $ds2$, the winding of relay C, contacts $b4$ to the wiper $rf5$ making connection with the pulse lead. The switch NS takes one step 45 for each impulse and the relay C which is of the slow to release type remains operated during the series of impulses. Contacts $c3$ close the obvious circuit for the relay DS which is also of the slow to release type. 50 When the relay C releases a transitory circuit is completed from ground at $b1$ through contacts $c1$, $ds3$, to the wipers $ns4$, 5, 6, and 7 which will cause the operation of a certain combination of the relays WA, WB, WC and WD depending upon the digit dialled. A locking circuit provided for each relay 55 through contacts such as $wa4$ to ground at $b1$. When the relay DS releases the storage operating circuit is opened at $ds3$ but a driving circuit for the numerical switch NS is closed through its interrupter springs, contacts $ds4$, bank contact and wiper $ns1$ to ground at $b1$. This circuit is maintained until the numerical switch reaches position 12 where it remains 60 waiting for the next set of impulses.

The relays XA, XB, XC and XD are operated in a similar manner for the hundreds digit and the relays YA, YB, YC and YD for the tens digit. The units digit is stored by the numerical switch NS and in this position the relay DS is maintained after the relay C releases through the bank contact and wiper $ns1$ to ground at $b1$. The continued operation of the relay DS opens at $ds2$ the impulsive circuit and prevents any further movement of the numerical switch NS in response to the subscriber dialling. The condition of relay operation for the thousands digits is such that either the relay WA or WC is always operated and in consequence when the thousands impulses have been received a ground will be extended from $h1$, $bb3$, the wiper $sm1$, bank contact 49, $wa1$ (or $wc1$) $j3$, $j1$, $ss2$ causing the reoperation of relay CC. The thousands impulses are now sent out, SM being stepped on in synchronism. The relays SA and SZ operate, as already described, the ground for operating relay SZ being connected by contacts of the relays WA, WB, WC or WD. The circuit for re-energizing the relay CC in position 61 is dependent upon the contacts $xa1$ and $xc1$, the corresponding circuit for relay SZ being completed through contacts of the relays XA, XB, XC and XD. In position 73 the circuit for relay CC is established through contacts $ya1$ or $yc1$ and the circuit for relay SZ through contacts of the relays YA, YB, YC and YD. As has already been explained the relay DS remains operated after the units digit and the circuit for the relay CC in position 84 is established through contacts $ds1$ and $ya1$ or $yc1$. The circuit for the relay SZ is established by the position of the numerical switch NS, ground being extended from $b1$ through $c1$, $ds3$ and wiper $ns6$ to the relative bank contact associated with wiper $sm2$. In position 96 a ground is extended from $h1$, $bb3$ through the wiper $sm1$, to the wiper $rf1$ which is connected to the K lead to the second bye-path and causes the operation of the relay G in that circuit. The second bye-path extends the talking conductors and subsequently opens the circuit for the relay B which releases. Contacts $b2$ open the circuit for relay H but the short circuit provided by the contacts $b3$ is removed from the second winding of the relay H which will remain operated so long as there is a feed coming back over the positive and negative wipers $rf9$ and $rf0$. During this period the relay DS is maintained through the wiper $ns1$, through contacts $h5$ to ground. As soon as the alternative circuit for relay H is removed the register translator connects the positive and negative wipers to the zone metering terminals ma and mb by means of contacts $h4$ and $h3$. The wiper $cm5$ of the code switch is still connected to ground through contacts $bb4$ and $j4$ and the bank 105 110 115 120 125 130

contacts are adapted to be connected either to the terminal MA, the terminal MB or through a resistance to the relay A. The operation of relay A makes ground through contacts a_1 and a_2 to both the terminals MA and MB. In this way jumpering particular to each set of code terminals may be completed so as to ground the terminal MA or the terminal MB or both terminals. The circuit for the relay BB was opened at h_1 when the relay H released but being of the slow to release type it does not release immediately and the metering potential is maintained until relay BB releases. The contacts h_1 open the circuit for relay DS and when this relay releases the numerical switch NS returns to its home position through its interrupter springs, contacts ds_4 , the off normal bank and wiper ns_2 , to ground at b_1 . The sending switch SM returns home through its interrupter springs, the off normal bank and wiper sm_3 , the home position and wiper ns_2 to ground at b_1 .

If the register translator is required to complete a call over a direct junction no translation being necessary ground is connected to wiper of 6 and the relays H and LN operate together when HH in the bye-path energizes. The contacts ln_2 switch the circuit for the relay CA to a particular set of contacts associated with the code switch CM so that the code switch takes up a position independent of the setting of the finder switch RF. Contacts ln_1 open the operating circuit of the relay CB which would otherwise be closed when relay CC operated. The bank terminals associated with the wipers cm_1, cm_2, cm_3, cm_4 in this position are jumped to the CO terminals in positions 2, 13, 40, 25 and 37 so that a circuit for the relay SZ is completed at the same time as the circuit for the relay SA and in consequence the short circuit across the impulse springs LS1 is maintained. The sender switch advances immediately to position 49. The storing and sending of the numerical impulses is identical with the operation already described.

If the register translator is to be used for completing a connection to a call indicator exchange, the relay J is operated over wiper rf_7 . The contacts j_4 complete a circuit for the relay BB through contacts cj_1 . The same ground is extended through the wiper sm_1 , contacts eb_2 , contacts j_1 , through the interrupter springs MS2 to the sender switch SM causing that switch to take one step. In position 2 ground is extended through contacts j_2 and j_1 to the interrupter springs and the stepping is maintained until the switch reaches position 49. In this position the sender switch waits until all the numerical impulses have been received at which time ground is extended through contacts b_1 , wiper and bank contacts ns_3 , winding of relay CJ, bank contact and wiper sm_5 , contacts j_7

to the negative wiper rf_9 . This signal causes an operation in the manual exchange and when the de-coding equipment is available the battery on the negative lead is removed. The operation of the relay CJ opens the circuit for relay BB which releases providing an alternative circuit for relay CJ independent of the wiper sm_5 and also completes the stepping circuit from ground at j_4 through wiper sm_1 , contacts w_1 or w_1 , bb_1 , j_1 , and the interrupter springs MS2 to the magnet SM. The sender switch advances to position 61 and waits in this position until the de-coding equipment is ready at which time the relay CJ releases as already explained. The relay BB in reoperating disconnects the relay CJ from the negative line and closes a further stepping circuit through contacts xa_1 or xc_1 and bb_1 . In position 62 the code sending commences, ground being connected to the positive wiper and battery being connected to the negative wiper if the relay WA is normal. In position 63 the negative line is connected to ground and the positive line to light or heavy battery depending upon the condition of the contacts wb_1 . In position 64 both lines are disconnected but in position 65 the positive line is grounded and the negative line connected to battery if the relay WC is normal. In position 66 the negative line is grounded and the positive line is connected to light or heavy battery depending upon the condition of the contacts wd_1 . In positions 67-72 further impulses are sent depending upon the condition of relays XA, XB, XC and XD and in positions 74-79 further impulses are sent depending upon the condition of relays YA, YB, YC and YD. In position 80 the negative line is connected to battery and the positive line is connected to certain positions of the bank ns_4 . These positions are complementary to the positions connected to the relays WA, XA, YA. In position 81 the positive line is connected to battery through a low resistance and the negative line is connected through wiper ns_5 to ground in such a way that there will be no additional resistance unless the units digit be of a value that the relays WB, XB and YB would not operate. As a result a heavy negative pulse will be sent for certain digits and a light negative pulse for other digits in the same way as a discrimination is made by the contacts wb_1 . In position 82 both lines are disconnected. In position 83 a positive pulse is sent through bank contacts and wiper ns_4 in such positions that correspond to digits which would not operate the relays WC, XC and YC. In position 84 a light or heavy negative pulse is sent by means of the position of the wiper ns_7 . In position 85 and later position the positive and negative lines are left disconnected. In position 96 the ground through contacts j_4 and the wiper sm_1 is connected

through wiper r_f1 to the K lead causing the operation of the relay G of the second bye-path. Relay G switches through the conversational conductors and causes the release

5 of relay J. The homing circuit for the switches NS and SM will be as already described for a normal call.

The repeater to tandem shown in Figure 5 will be operated in the following circuit:—

- 10 The testing circuit will be through the bye-path test conductor BPT, contacts hs_4 , bs_2 , to battery. After seizure ground will be extended over the bye-path test causing the operation of the relay BS and a circuit will 70
- 15 be completed for the relay JS through contacts bs_1 , hs_2 and js_1 . Relay HS is shunted and does not operate at this time. The impulse circuit is extended through contacts hs_1 and hs_3 through the repeater circuit 75
- 20 without repetition. After the impulses have been sent ground is extended to the hold wire if the connection has been routed through an operator's position and no transmission bridge is required. In such case the relay JS 80
- 25 is short circuited and closes the circuit for the relay HS through contacts js_4 . Relay HS opens the bye-path testing circuit at contacts hs_4 and the relay BS releases. Contacts hs_1 and hs_3 connects the BP+ and BP- 85
- 30 leads to the relays MZ and MX respectively which are connected to battery. A combination of the relays MX and MZ are operated but owing to the fact that relay BS 90
- 35 is released the relays MX and MZ are not maintained after the register has been disconnected. For a normal call the relay JS 95
- 40 is not short circuited and the relay AS operates over the contacts js_2 and js_3 . Relay B is locked over contacts as_1 . Contacts as_2 100
- 45 close the obvious circuit for relay HS through contacts ds_1 . The contacts as_3 and as_4 complete the conversational circuit 105
- 50 through the retard IS and the shunt field relay DS. The operation of the contacts hs_3 and hs_1 complete the circuit to the relays 110
- 55 MX and MZ one, or other, or both of which may operate and lock over contacts ms_1 or ms_2 and bs_3 to ground. The ground is extended to the start lead S to common metering equipment through contacts hs_5 , ms_2 or ms_2 . when the circuit for the relay HS is 115
- 60 opened through the operation of the shunt field relay DS. The common metering equipment makes connection with the circuit 120
- 65 requiring metering and receives a discriminating earth over contacts ms_3 and/or ms_3 and hs_6 . A fourth condition may be signalled if neither MX nor MZ is operated. Booster potential is applied once or more via lead B to 125
- 70 the hold wire in consequence. The relays MX and MZ are short circuited via lead SC at the time of metering to remove the ground from the start point. When the calling subscriber releases the contacts as_1 open the circuit for relay BS and the contacts bs_1 re-

move the ground from the hold conductor which is holding the various switching relays.

What is claimed is:

1. In a telephone system comprising a plurality of exchanges and junction lines interconnecting said exchanges, the combination of register translators at said exchanges, means independent of said register translators for establishing a direct connection between one exchange and another, means for establishing an indirect connection between said exchanges under control of said register translators, and means whereby calls over said direct connection may be set up independently of said register translators under direct control of a calling party. 70

2. A telephone system as claimed in claim 1 in which for all inter-exchange calls a register translator at the calling exchange is connected for use and means is provided to release said register translator unused if a direct connection between one exchange and another is available. 75

3. In a telephone system comprising a first exchange, a plurality of other exchanges and a tandem exchange, the combination of a register translator at said first exchange, direct junction lines between the first exchange and said other exchanges, junction lines between the tandem exchange and said first exchange and said other exchanges, means whereby a calling party at said first exchange may establish a connection automatically to a called party at any one of said other exchanges over said direct junction lines independently of said register translator, and means operative if all the direct junction lines between said first exchange and the exchange of the called party are busy, to cause said register translator to establish an alternative connection to the desired exchange via said tandem exchange. 90

4. A telephone system as claimed in claim 3 wherein the number of direct junction lines between the first exchange and each of said other exchanges is substantially less than the number necessary to carry the traffic between said exchanges, and the number of junction lines between the first exchange and the tandem exchange is sufficient to carry the traffic between the first exchange and said other exchanges for which direct junction lines are not provided, in addition to other tandem traffic from said first exchange. 95

5. A telephone exchange system, according to claim 3 wherein a plurality of junction groups is provided from one exchange to a plurality of other exchanges and means is provided whereby a modification to the size of one of said groups will satisfy a change of traffic intensity on any one or more of said junction groups. 125

6. In a telephone system comprising a first exchange, a plurality of other exchanges and 130

a tandem exchange, the combination of a register translator at said first exchange, direct junction lines between the first exchange and said other exchanges, junction lines between the tandem exchange and said first exchange and said other exchanges, means independent of said register translators for selecting one of said junction lines from said first exchange on an inter-exchange call and means whereby the register translator controls the setting up of the connection over certain of said junction lines.

7. In a telephone system comprising a plurality of exchanges and junction lines interconnecting said exchanges, the combination at one at least of said exchanges of a plurality of discriminating circuits each of which is associated with a plurality of talking circuits, a plurality of register translators each associated with a plurality of said discriminating circuits and means in said discriminating circuits which determine whether or not a register translator is to be used in setting up a connection.

25 8. A telephone exchange system, the combination of single motion selector switches, a number of talking circuits, a plurality of control circuits each of which is associated in common with a plurality of talking circuits, a plurality of register translators each associated in common with a plurality of control circuits, each control circuit comprising discriminating means which is adapted to respond to a code digit or digits and to determine whether a register translator is to be used in setting up a connection.

9. A telephone system according to claim 8 wherein each control circuit comprises a bye-path switch which is adapted to select a free outlet in a wanted direction and means is provided for extending an impulsive circuit over the selected outlet either from the calling party's circuit or from the sending circuit of a register translator.

45 10. In a telephone exchange system the combination of a first group selector, a plurality of second group selectors accessible from said first group selector, inter-exchange junction lines to different exchanges accessible respectively to said second group selectors, inter-exchange junction lines to the same exchange accessible to all of said second group selectors and register translators associated with said second group selectors and adapted to control the setting up of calls over said last mentioned junction lines.

11. In a telephone exchange system, the combination of single motion switches, a control circuit common to said switches, a register translator comprising a code switch adapted to receive a plurality of code digits, a switch in said control circuit adapted to receive a plurality of code digits, said switch being inter-connected with said code switch whereby the number of translating positions

provided on the code switch is less than the number of exchanges to which access is possible from said single motion switches.

12. A telephone exchange system according to claim 3 wherein calls between certain exchanges can be set up over direct junctions between the originating and terminating exchanges or via indirect junctions through an intermediate exchange or exchanges and the number of indirect junctions outgoing from an exchange, over which a particular terminating exchange is accessible is greater than the number of direct junctions to the said terminating exchange.

13. A telephone exchange system according to claim 10, in which each outgoing selector switch has access to junctions outgoing to each exchange identified by a particular first code digit.

14. In a telephone exchange system the combination of an outgoing selector switch which has access to a group of direct junctions to a distant exchange and to a group of indirect junctions over which access to the same distant exchange may be obtained, means for causing said switch to search over said direct junctions and if none of said junctions is free to continue automatically to search over said indirect junctions, a register translator, and discriminating means adapted to cause said register translator to control the setting up of a connection over said indirect junctions.

15. In a telephone exchange system comprising register translators, means whereby an inter-exchange connection may be set up independently of said register translators, means whereby the register translators are adapted to store numerical digits only in the event the direct connection to the distant exchange is not established for the receipt of dialled impulses and means in said register translator responsive on the establishment of said connection in the distant exchange to cause said register translator to re-transmit said numerical digits for setting up the connection in the distant exchange.

16. In a telephone exchange system comprising automatic and manual exchanges interconnected by junction lines, the combination at said automatic exchanges of register translators, means for setting up inter-exchange connections independently of said register translators under control of a calling party, means for establishing a connection between an automatic exchange and a manual exchange, and means in said register translator operative on connection to a manual exchange to translate the numerical digits of a wanted number into code impulses for transmission to said manual exchange.

17. In a telephone exchange system the combination of a plurality of selector switches and talking circuits, a plurality of bye-path circuits each associated in common with

a plurality of said selector switches, a plurality of register translators each associated in common with a plurality of said bye-path circuits, a plurality of inter-exchange junction lines accessible to said selector switches, means whereby said register translators control the setting up of inter-exchange connections over said bye-path circuits and certain of said junction lines and means for extending the talking circuits to replace said bye-path circuits.

18. In a telephone exchange system the combination of a plurality of selector switches and talking circuits, a plurality of bye-path circuits each associated in common with a plurality of said selector switches, a plurality of register translators each associated in common with a plurality of said bye-path circuits, a plurality of inter-exchange junction lines accessible to said selector switches, means whereby said register translators control the setting up of inter-exchange connections over said bye-path circuits and certain of said junction lines and means for extending the talking circuits to replace said bye-path circuits and means adapted to operate during the setting up of a call with the aid of a register translator to prevent said replacement until all the digits have been transmitted from the register translator.

In witness whereof we hereunto subscribe our names this seventeenth day of December, 1930.

ESMOND PHILIP GOODWIN WRIGHT.
GEORGE CLIFFORD HARTLEY.
